F. W. THOMPSON

VENTILATED GARMENT

Filed Sept. 7, 1926

F.W.Thompson,
INVENTOR

INVENTOR

ATTORNEY.

UNITED STATES PATENT OFFICE.

FULLER W. THOMPSON, OF ARCADIA, CALIFORNIA.

VENTILATED GARMENT.

Application filed September 7, 1926. Serial No. 183,776.

The present invention relates to garments and pertains more particularly to knickerbocker trousers or "knickers", such as are worn by golfers, hikers and the like.

5 The invention has for its principal object the provision of a garment of the class described which can be worn in hot weather with greater comfort.

An object of the invention is to provide 10 for efficiently ventilating such garments so that the limbs of the wearer are not enclosed in an air tight garment. Knickers are commonly provided with straps or the like which girdle the legs closely just below 15 the knees. Unlike other similar garments, all portions of the body within the knickers are completely isolated from extraneous air and are accordingly quite uncomfortable, particularly in hot weather. Garments of 20 this class are often quite dressy.

It is therefore one of the principal objects of the invention to provide suitable ventilating means for such garments whereby extraneous air may enter the garment and 25 have free circulation around the limbs.

Another and important object of the invention is to provide such garments with suitable ventilating means, without detracting from the conventional appearance of 30 same, and whereby ventilation may be applied to golf knickers and other "dressy" garments without departing from the accepted principles of good taste.

Another object of the invention is to provide 35 knickers with suitable ventilating means which are at all times inconspicuous and even invisible.

Still other objects and advantages of my 40 invention will appear hereinafter.

I have illustrated my invention by the accompanying drawings in which:

Figure 1 is a perspective view of a golfer 45 wearing a pair of knickers which embody my invention.

Figure 2 is a perspective of such knickers.

Figure 3 is a view in cross section of the 50 lower part of a leg portion of such knickers.

Figure 4 is a view in elevation of the lower end of a leg portion of a modified embodiment of my invention.

Figure 5 is analogous to Fig. 4 and shows 55 still another modification.

In the drawings I have shown a pair of knickers 1, which are provided at the waist 60 with the usual belt portion 6, and at the lower extremities with the usual straps or

bands 7. Said bands completely encircle the legs 8, of the wearer, just below the knees. Referring to the detail cross section in Fig. 3, the usual spaces, such as 9, which exist 60 within the garment, are normally isolated by said band so that the interior has no ventilation.

My invention may be variously applied to knickers of various styles, and for the sake 65 of illustration I have shown one practical embodiment of my invention and a modification thereof.

In the form shown in Figs. 1 to 3, inclusive, that portion of the garment material, 70 just above the leg band, is provided with one or more suitably large perforations or openings 10. These perforations are preferably limited to the particular area designated. In the form of the invention now being described, each opening is defined by a suitable metal binding or eyelet 11. Such eyelets 75 protect the adjacent material from becoming frayed, and further provide rigidity around the openings. Several such openings and eyelets may be provided in an annular series 80 encompassing each leg of the garment.

When the garment is properly disposed upon a person, with the bands encompassing respective limbs, the material of each leg 85 portion folds over, as at 12. Accordingly, the portion 14, of the garment, in which the eyelets are disposed, is hidden from view. Said portions 14 are rendered somewhat 90 rigid by the metal eyelets and have a tendency to stand out at an appreciable angle of inclination with regard to the vertical plane. As a consequence the openings are directed 95 in a downward direction and are suitably spaced from adjacent fabric as well as from the limbs of the wearer.

Referring particularly to the cross section in Fig. 3, it will be apparent that the space 9 is of appreciable cross sectional area and provides for air currents, as indicated by the 100 arrows, moving inwardly and outwardly through the said openings.

In the normal functioning of the limbs, as in walking, or in bending the knees, or in moving the upper part of the body, the 105 characteristic movement of the leg portions of the garment will produce a bellows action or pumping action which will positively insure movement of air into or out from such spaces, as the case may be.

In the form of the invention shown in Fig. 4 the openings are covered by suitable

screen-like material 16, such as fine mesh of fine non-corrosive wires. Such screens will provide certain rigidity to the garment at points immediately above the knee, and will cause the garment to hang properly while providing suitably large air passages. Such screens will sift out dust and the like while permitting the air to circulate freely.

In the form shown in Fig. 5 certain portions of the material are removed at spaced intervals to provide openings 10'. Intermediate portions 17, of the material, form spaced fingers which connect the leg band with the main leg-portion of the garment. The material of the garment above the openings has a tendency to hang almost straight downward so that the openings are out of sight, while air currents are free to enter the leg-portions of the garment between the spaced fingers 17.

All of the embodiments described provide excellent ventilation and make the garment cool, comfortable and healthful, and it will be apparent that I have provided such ventilation without detracting from the usual appearance of such garments, and while I have shown and described specific embodiments of my invention, I do not limit myself to any specific construction or arrangement of parts, and I may alter same as I desire without enlarging the scope of my invention as set forth in the appended claim.

I claim:

In knickerbocker trousers, a leg portion, a leg encircling band at the lower extremity of said leg portion; said leg portion being provided with an annular series of apertures immediately above said band.

FULLER W. THOMPSON.
